UNITED STATES PATENT OFFICE

154,806

DESIGN FOR A BUS

Eric P. Ramstrum, Grosse Pointe Park, Mich.

Application October 15, 1947, Serial No. 141,916

Term of patent 3½ years

(Cl. D14—3)

To all whom it may concern:

Be it known that I, Eric P. Ramstrum, of Grosse Pointe Park, County of Wayne, and State of Michigan, have invented a new, original, and ornamental Design for a Bus, of which the following is a specification, reference being had to the accompanying drawing, forming part thereof, in which:

Figure 1 is a perspective view of a bus, showing my new design.

Figure 2 is a side elevational view thereof.

The side of the bus opposite to that shown in the drawings is the same as that illustrated except that the doors are omitted and the windows are continuous for the length of the bus, and the rear end of the bus is generally conventional in design.

I claim:

The ornamental design for a bus, substantially as shown and described.

ERIC P. RAMSTRUM.
